UNITED STATES PATENT OFFICE

SIVIL PAULSON, OF SIOUX FALLS, SOUTH DAKOTA.

FIREARM.

950,577.

Specification of Letters Patent. Patented Mar. 1, 1910.

Application filed February 12, 1908. Serial No. 415,523.

To all whom it may concern:

Be it known that I, SIVIL PAULSON, a subject of the King of England, residing at Sioux Falls, in the county of Minnehaha 5 and State of South Dakota, have invented certain new and useful Improvements in Firearms, of which the following is a specification, reference being had therein to the accompanying drawings.

This invention relates to double-barreled firearms; and its object is the provision of means whereby the charges in both of the barrels may be fired from a single trigger and be capable of being manipulated to cause either of the barrels being discharged in advance of the other.

With these and other ends in view the invention consists in the novel construction, adaptation and combination of devices, as 20 will be hereinafter described and claimed.

In the drawings, Figure 1 is a longitudinal vertical section of a portion of a gun wherein is shown in elevation devices embodying my invention. Fig. 2 is a view of 25 the same shown partly in plan and partly in horizontal section. Figs. 3 and 4 are side elevations to illustrate two phases of the action of the invention. Fig. 5 is a perspective view of the trigger block. Fig. 6 30 is a like view of the controller block. Figs. 7 and 8, respectively, are similar views of the sears for the right and left hand hammers.

The type of gun illustrated in the drawings is of that type known as "hammerless" as best illustrating the manner of carrying out the invention, though the invention is equally applicable to the other class or "hammer" guns, as will be referred 40 to later.

The numeral 10 designates the stock, 11 the bore, and 12 the frame, which may be constructed and arranged as ordinary or in any suitable manner.

45 13 represents the hammer for the right hand barrel and 14 the hammer for the left hand barrel which hammers are pivoted on a pin 15 and are cocked by a suitable lever, or levers, such as 16, see Fig. 1, and are 50 severally provided with main-springs, as 17. For each of the hammers there is a sear which sears are pivoted upon a fixed pin 18 and are arranged to be engaged by sear springs 19 with the respective hammers in 55 notches 13' and 14' therein provided when such hammers are in cocked condition, as

best shown in Fig. 3. Of said sears the right hand one 20 has upon its rear arm a finger 20' which is directed inwardly, that is, toward the left hand with respect to the 60 gun barrels; and the left hand sear 21 has a finger 21' directed oppositely or toward the right and is desirably chamfered, as at 21'.

22 is a trigger-block which is fulcrumed 65 in proximity to its front end on a pin 23 and has a trigger 22' extending downwardly therefrom so as to protrude below the gunstock. Coupled to said block is another block 24, or controller as it will be herein 70 after designated, which is capable of longitudinal motion with respect to the trigger-block. Such connection is desirably had by the provision of an inverted T-shaped base 24' to the controller which fits in a correspondingly shaped way 22'' in the trigger-block. Extending downwardly from the controller is a lug 24'' to serve as an abutment between which and the rear end of a cavity 22''' of the trigger-block is spring 25 80 serving to press the controller forwardly.

An arm 24''' extends forwardly from the controller and is arranged to have its extremity coact with a cam 13'' provided upon one of the hammers so that when the hammer is cocked the controller will be affected 85 to move the same rearwardly in opposition to the spring 25. In the upper right hand corner of the controller are spaced notches 90 *a* and *b* of suitable sizes to receive the finger 20' of the right hand sear when the controller has been moved to present the respective notches thereto. Upon the opposite upper corner of the controller is a similar notch *c* to receive the finger 21' of the other 95 sear when the controller is adjusted to have the finger of the sear 20 in position to be engaged by the space *d* intermediate the aforesaid notches *a* and *b*.

26 is a hook which is pivotally connected 100 to an arm 27 extending upwardly from the trigger-block and is arranged to have its bill 26' engage the controller in the notch *c* when the latter is in its rear-most position whereupon the finger 21' of the left hand sear will 105 be in position to be engaged by the controller immediately in front of such notch, as at *e*. The eccentricity of the cam 13'' is, however, insufficient to cause the movement of the controller into the position to present 110 the notch *c* for engagement with said hook and I accordingly supply supplementary de-

5 vices for attaining such movement. These devices may consist in an angular shaped shifter 28 having one of its arms 28' disposed so as to extend into the forward end of the block cavity 22''' and when moved rearwardly carry the controller therewith through engaging the lug 24''. The other arm 28'' protrudes through a slot 11' in the gun frame and affords a finger hold for the operator. The arm 28' of said shifter is conveniently supported and guided by providing a longitudinal slot 28''' therein and through which extends said fulcrum pin 23 and a guide pin 29.

10 15 30 is a spring serving to normally retain the shifter in its forward inoperative position, and a spring 31 may be employed to yieldingly retain the hook 26 upon occasion against the top face of the controller or in 20 the notch *c* thereof.

25 The operation of the invention when applied to a hammerless gun is as follows: In cocking the gun the hammer-cam 13'' acting against the arm 24''' of the controller 24 forces the latter rearwardly into the position in which it is illustrated in Fig. 3 and whereat the finger 20' of the right hand sear will be directly above the controller part *d* and the finger 21' of the other sear above 30 the notch *c*. When this condition prevails it is evident that by tilting the controller upwardly, as represented in Fig. 4, and through a pull upon the trigger, that the controller will act against the right hand sear to tilt it and to disengage this sear from the hammer, while the finger 21' of the other sear will not be affected by the controller. The hammer 13 is thus released and through 35 the influence of the main spring therefor fires the charge in the right hand barrel, and, in so doing, the cam is turned to afford of sufficient forward movement to the controller to have the notch *a*, and the part *f* to the rear of the notch *c* respectively below 40 the fingers 20' and 21' of the right and left hand sears. Under these circumstances another pull upon the trigger will affect only the left hand sear to cause the release of the corresponding hammer and result in the discharge of the left hand barrel. When it is 45 desired to fire the left hand barrel prior to the other, the shifter 28 is manipulated to move the controller rearwardly to permit the hook 26 engaging the same in the notch *c*, whereupon the fingers 20' and 21' will be 50 respectively positioned above the notch *b*, and the part *e* in advance of the notch *c*. The hammers being cocked, and under such assumed disposition of the controller, a pull 55 upon the trigger will be inert as to the right hand sear, while the left hand one will be affected to release its hammer during the early part of the tilting movement of the controller and the subsequent withdrawal of 60 65 the hook from the engaged notch by the

chamfered face 21'' of the finger 21' acting as a wedge against the sloping face 26' of the hook. The block being thus freed is moved by the spring 25 forwardly to abut with the cam 13'' of the cocked hammer 13 70 and the sear finger 20' above the controller part *d* resulting in the discharge of the right hand barrel when another pull is imparted upon the trigger. From the foregoing it is evident that the cocking of the 75 hammers of themselves serve to automatically position the controller so that the right hand barrel will be discharged through the first trigger pull, and a succeeding pull will discharge the other barrel. It is furthermore evident that the left hand barrel may be first discharged through the agency of 80 the shifter 28.

With hammer guns the shifter, and the hook 26 for restraining the controller are 85 not required as, where the left hand barrel is to be first discharged, it is only necessary to cock that hammer by hand and fire the same while the controller is in its most forward position, and the right hand hammer 90 in being similarly cocked displaces the controller so as to be positioned to fire the right barrel when the trigger is again pulled, and hence the notch *b* may be omitted in applying the invention to this class of guns. 95

Having described my invention, what I claim is,—

1. A double barrel fire-arm, comprising in combination with the gun hammers, a cam controlled by one of said hammers, a tiltable trigger block, a sear for each of said hammers, said sears each having a finger upon its rear end, a controller slidably mounted on said trigger block and provided with an arm in engagement with said cam, said controller having recesses adapted to receive said fingers on said sears, a spring inclosed in said trigger block for normally pushing said controller forwardly with relation to said block, means to slide said controller 100 rearwardly of said block, and means pivoted to said trigger block to hold said controller 105 in said rearward position.

2. A double barrel fire-arm, comprising in combination with the gun hammers, a cam controlled by one of said hammers, a tiltable trigger block having a recess formed therein, a sear for each of said hammers, said sears each having a finger upon its rear end, a controller slidably mounted on the upper face 115 of said block, and having a lug depending in said recess, a spring bearing between said lug and said block to normally maintain said controller in a forward position, a forwardly projected arm formed on said controller and in normally operative engagement with said cam, a member projecting and operative in said recess in said block to slide said controller out of engagement with said cam, and a depending member to lock said arm out of 120 125 130

- such engagement, said controller having means to render either of said sears operative on said hammers as said controller is moved.
- 5 3. A double barrel fire-arm, comprising in combination with the gun hammers, a cam controlled by one of said hammers, a tilt-able trigger block having a recess formed therein, a sear for each of said hammers, 10 said sears each having a finger upon its rear end, a controller slidably mounted on the upper face of said block, and having a lug depending in said recess, a spring bearing between said lug and said block to normally maintain said controller in a forward position, a forwardly projected arm formed on said controller and in normally operative engagement with said cam, a member projecting and operative in said recess in said block 15 to slide said controller out of engagement with said cam, and a depending member to lock said arm out of such engagement, said controller having a series of recesses formed in its upper face into which said fingers of 20 said sears are adapted to predeterminedly fall as said block is moved in either direction, whereby to render said sears inoperative on said hammers.
4. A double barrel fire-arm, comprising in combination with the gun hammers, a cam 30 controlled by one of said hammers, a tilttable trigger block having a recess formed therein, a sear for each of said hammers, said sears each having a finger upon its rear end, a controller 35 slidably mounted on the upper face of said block, and having a lug depending in said recess, a spring bearing between said lug and said block to normally maintain said controller in a forward position, a forwardly projected arm formed on said controller and in normally operative engagement with said cam, a member projecting and operative in said recess in said block 40 to slide said controller out of engagement with said cam, and a depending member to lock 45 said arm out of such engagement, said controller having means to render either sear inoperative on said hammers and said controller sliding member being normally in position to be manually operated. 50

In testimony whereof I affix my signature in presence of two witnesses.

SIVIL PAULSON.
